Primary Examiner — Janice Hallmark(74) *Attorney, Agent, or Firm* — Muncy, Geissler, Olds & Lowe, P.C.(57) **CLAIM**

The ornamental design for a ceiling fan housing with light kit, as shown and described.

DESCRIPTION

FIG. 1 is a bottom front perspective view of a ceiling fan housing with light kit showing the claimed design;

FIG. 2 is an enlarged bottom front perspective view thereof;

FIG. 3 is an enlarged front elevational view thereof;

FIG. 4 is an enlarged rear elevational view thereof;

FIG. 5 is an enlarged left side elevational view thereof;

FIG. 6 is an enlarged right side elevational view thereof;

FIG. 7 is an enlarged top plan view thereof; and,

FIG. 8 is an enlarged bottom plan view thereof.

Broken lines illustrate portions of the ceiling fan housing with light kit that form no part of the claimed design.

Additional broken lines showing ceiling fan blades in FIGS. 1-8 and a ceiling fan downrod in FIGS. 1-7 depict environment and form no part of the claimed design.

1 Claim, 8 Drawing Sheets(56)
